UNITED STATES PATENT OFFICE.

CHARLES CALHOUN RANKIN, OF LOUISVILLE, KENTUCKY.

PLOW-STOCK.

No. 919,296.

Specification of Letters Patent.

Patented April 20, 1909.

Application filed June 27, 1908. Serial No. 440,683.

To all whom it may concern:

Be it known that I, CHARLES CALHOUN RANKIN, a citizen of the United States, residing at Louisville, in the county of Jefferson and State of Kentucky, have invented certain new and useful Improvements in Plow-Stocks; and I do declare the following to be a full, clear, and exact description of the invention, such as will enable others skilled in the art to which it appertains to make and use the same, reference being had to the accompanying drawings, and to the figures of reference marked thereon, which form a part of this specification.

15 My invention relates to plow stocks and has for its object to provide a device of this kind upon which may be attached various kinds of blades, shovels, sweeps, etc.

20 A further object of my invention is to provide a plow stock which is constructed entirely of metal and which can be quickly and easily knocked down for convenient shipment, and which can be as readily assembled.

25 A further object of my invention is to provide a device of this class which is particularly simple in its construction, cheap and easy to manufacture, strong, durable and efficient.

30 A further object of my invention is to provide a device of this kind wherein the standard may be adjusted to any desired angle, and which has the part so constructed and arranged that the standard and beam clamp become tighter as the strain increases on the standard.

35 With all these objects in view my invention consists in the novel construction and arrangement of the parts, and my invention particularly consists in the novel construction of the beam; and my invention also consists in the combination between the beam, handles and standard, all of which will be first fully described and afterward specifically pointed out in the appended claims.

40 Referring to the accompanying drawing: Figure 1 is a perspective view of a plow stock constructed in accordance with my invention. Fig. 2 is a longitudinal sectional view the end of the handles and end of the beam being broken away.

45 Like numerals of reference indicate the same parts throughout the several figures in which;

50 1 indicates the stock which comprises the beam 2, handles 3, standard 4 and standard brace 5.

Referring to Fig. 2 it will be seen that the extreme ends of the beam 2 are flattened, the forward flattened ends 6 forming its clevis and the rear end 7 being flattened to form a 45 degree extension, the rear flattened portion being wider than the diameter of the metallic tubular beam.

As will appear from Fig. 1 the lower ends 8 of the handles 3 are flattened preferably in a confined die in such manner that the said flattened ends will be no wider than the original diameter of the tube.

10 indicates the beam clamp which is composed of two sections 11 and 12 which encompass the beam 2, said clamp 10 being slidable on the beam 2 as indicated in dotted lines in Fig. 2. The standard 4 is formed like a loop, the upper ends 13 straddling the lower portion of the beam clamp 10 as clearly shown, and is secured thereon by means of a bolt 14. The handles 3 are secured on the flattened end 7 of the beam 2 by means of suitable bolts or rivets 15, the extreme lower ends of the handles 3 accommodating the standard brace 5 which is secured to the ends of the handles by means of a bolt or rivet 16, which standard brace 5 is pivoted to the standard 4 by means of a suitable bolt or rivet 17.

Having thus described the several parts of my invention its operation is as follows: The beam 2 being constructed preferably from a hollow tube has its ends flattened as before described. The handles which are preferably tubular have their lower ends flattened as shown in Fig. 1 and are secured to the flattened end 7 of the beam by means of suitable bolts or fastenings 15. The beam clamp 10 is secured on the beam 2 and the standard 4 fastened to the clamp as shown in Fig. 1; the standard brace 5 being then secured in position shown in Fig. 1 the stock is then ready to receive its blade.

In order to adjust the standard to any desired angle the clamp 10 is loosened so that the same is slidable on the beam 2. Any movement of the clamp 10 on the beam 2 obviously alters the angle of the standard 4 as shown in dotted lines in Fig. 3 and by this simple method any desired adjustment can be quickly and readily accomplished.

As will appear from the drawing the bolt or rivet 17 which connects the standard brace 5 to the standard 4 becomes the fulcrum for the standard 4; consequently all strain applied to the standard 4 acts on the fulcrum

17 which draws down on the beam clamp 2, thus having a tendency to tighten the clamp on the beam 2 and preventing all sliding or movement of the clamp 10 on the beam 2.

5 Having thus fully described my invention what I claim as new and desire to secure by Letters Patent of the United States, is:

- 10 1. A plow stock comprising a tubular metallic beam, handles, standard and standard brace, said beam being flattened at its forward end to form a clevis and flattened at its rear end, the portion at the rear end being wider than the diameter of the tubular beam, the lower ends of said handles being flattened to conform to the flattened end of said beam, a beam clamp for said beam to which beam clamp said standard is pivoted, said standard brace being pivoted to the flattened ends of said handles and pivoted to the said standard.
- 15
- 20

2. A plow stock comprising a tubular metallic beam, handles and a standard, the rear end of said beam being flattened to form a bearing for the handles, the lower ends of said handles being flattened to conform to the flattened surface of the said beam, said handles straddling the flattened surface of the said beam.

25 3. A plow stock comprising a tubular metallic beam, handles and a standard, the rear end of said beam being flattened to receive the handles, the lower ends of the said handles conforming to the flattened surface of the said beam.

30 In testimony whereof, I affix my signature, in presence of two witnesses.

CHARLES CALHOUN RANKIN.
